Des. 217,539
Patented May 12, 1970

217,539

AN ILLUMINABLE HOUSE MARKER

Winfred D. Wren, ½ Wren, Inc., 1024 S. Kealing Ave.,
Indianapolis, Ind. 46203

Filed Apr. 1, 1969, Ser. No. 16,527

Term of patent 14 years

Int. Cl. D8—03

U.S. Cl. D8—180

Fig. 1

Fig. 2

Fig. 3

FIG. 1 is a perspective view of an illuminable house marker showing my new design;

FIG. 2 is a rear elevation thereof; and

FIG. 3 is a bottom plan view thereof.

The indicia is shown in broken lines in FIG. 1 for illustrative purposes only and forms no part of the claimed design.

I claim:

The ornamental design for an illuminable house marker, as shown and described.
